UNITED STATES PATENT OFFICE

ROBERT O. HENDRICKSON AND CLARENCE M. EASON, OF CLEVELAND, OHIO,
ASSIGNORS TO WALLIS TRACTOR COMPANY, OF RACINE, WISCONSIN, A
CORPORATION OF WISCONSIN.

DESIGN FOR A TRACTOR-BODY.

45,302.

Specification for Design.

Patented Feb. 24, 1914.

Application filed August 27, 1913. Serial No. 787,029. Term of patent 14 years.

To all whom it may concern:

Be it known that we, ROBERT O. HENDRICKSON and CLARENCE M. EASON, citizens of the United States, residing at Cleveland, in the county of Cuyahoga and State of Ohio, have invented a new, original, and ornamental Design for a Tractor-Body, of which the following is a specification, reference being had to the accompanying drawing, forming part thereof.

The figure is a perspective of a tractor body of our new design.

We claim:

The ornamental design for a tractor body as shown.

ROBERT O. HENDRICKSON.
CLARENCE M. EASON.

Witnesses:

H. H. MCKEE,
B. E. KLINE.
